(57) **CLAIM**

The ornamental design for a notched utensil, as shown and described.

DESCRIPTION

FIG. 1 is a top perspective view of one embodiment of a notched utensil showing our design;

FIG. 2 is a bottom perspective view thereof;

FIG. 3 is a front elevation view thereof;

FIG. 4 is a rear elevation view being the same;

FIG. 5 is a left side elevation view thereof;

FIG. 6 is a right side elevation view thereof;

FIG. 7 is a top plan view thereof;

FIG. 8 is a bottom view thereof;

FIG. 9 is a top perspective view of another embodiment of a notched utensil showing our design;

FIG. 10 is a bottom perspective view thereof;

FIG. 11 is a front elevation view thereof;

FIG. 12 is a rear elevation view being the same;

FIG. 13 is a left side elevation view thereof;

FIG. 14 is a right side elevation view thereof;

FIG. 15 is a top plan view thereof;

FIG. 16 is a bottom view thereof;

FIG. 17 is a top perspective view of another embodiment of a notched utensil showing our design;

FIG. 18 is a bottom perspective view thereof;

FIG. 19 is a front elevation view thereof;

FIG. 20 is a rear elevation view being the same;

FIG. 21 is a left side elevation view thereof;

FIG. 22 is a right side elevation view thereof;

(Continued)

FIG. 23 is a top plan view thereof;
 FIG. 24 is a bottom view thereof;
 FIG. 25 is a top perspective view of another embodiment of a notched utensil showing our design;
 FIG. 26 is a bottom perspective view thereof;
 FIG. 27 is a front elevation view thereof;
 FIG. 28 is a rear elevation view being the same;
 FIG. 29 is a left side elevation view thereof;
 FIG. 30 is a right side elevation view thereof;
 FIG. 31 is a top plan view thereof;
 FIG. 32 is a bottom view thereof;
 FIG. 33 is a top perspective view of another embodiment of a notched utensil showing our design;
 FIG. 34 is a bottom perspective view thereof;
 FIG. 35 is a front elevation view thereof;
 FIG. 36 is a rear elevation view being the same;
 FIG. 37 is a left side elevation view thereof;
 FIG. 38 is a right side elevation view thereof;
 FIG. 39 is a top plan view thereof;
 FIG. 40 is a bottom view thereof;
 FIG. 41 is a top perspective view of another embodiment of a notched utensil showing our design;
 FIG. 42 is a bottom perspective view thereof;
 FIG. 43 is a front elevation view thereof;
 FIG. 44 is a rear elevation view being the same;
 FIG. 45 is a left side elevation view thereof;
 FIG. 46 is a right side elevation view thereof;
 FIG. 47 is a top plan view thereof;
 FIG. 48 is a bottom view thereof;
 FIG. 49 is a top perspective view of another embodiment of a notched utensil showing our design;
 FIG. 50 is a bottom perspective view thereof;
 FIG. 51 is a front elevation view thereof;
 FIG. 52 is a rear elevation view being the same;
 FIG. 53 is a left side elevation view thereof;
 FIG. 54 is a right side elevation view thereof;
 FIG. 55 is a top plan view thereof; and,
 FIG. 56 is a bottom view thereof.

The dotted lines represent portions of the notched utensil that form no part of the claimed design, while the dot-dash-dot line forms a boundary between the claimed and unclaimed subject matter and forms no part of the claimed design.
